UNITED STATES PATENT OFFICE

FREDERICK P. GORIN, OF SEATTLE, WASHINGTON, ASSIGNOR TO GORIN SHOCKLESSPEED TABULATOR COMPANY, OF KING COUNTY, WASHINGTON

TABULATOR REBOUND TRAP

Application filed August 11, 1928. Serial No. 299,082.

This invention relates to improvements in typewriting machines and more particularly to the tabulating mechanism. The principal object of the invention is to generally improve upon the constructions shown in the various 5 patents heretofore issued to me, and particularly the construction shown and described in Patent 1,411,997 issued to me on the fourth day of April 1922, in which I showed, described, and claimed means to positively "prevent rebound of the carriage past the pre-determined writing point". All of the said 10 patents require (a) that a carriage buffer be employed, because, in the said patents, it is necessary that the carriage pass beyond the pre-determined writing point and be returned thereto under the reflex action of the carriage buffer, in order to cause the setting or springing of the rebound lock. In other words, in 15 all of the said patents, the rebound lock would be inoperative and useless if no carriage buffer were employed. In the present invention it is optional whether a carriage buffer be employed or not, the rebound being effectually 20 prevented in either case, because, in the present invention the rebound lock is, as is also true regarding all of the said patents, normally unset or unsprung, but, in the present invention, means are provided which 25 causes the instant setting or springing of the rebound lock upon the operation of a tabulator key, whereas in all of the said patents the lock remains unset until the carriage has completed its run to the printing point. The 30 result of this is that in the present invention the carriage, even in its shortest run, cannot possibly rebound away from the pre-determined printing point. (b) In all of the said 35 patents, it sometimes happens, that the run of the carriage in a tabulating operation is so short that the blow resultant upon the impact of the tabulator stops with each other is not sufficient to completely and securely set the rebound lock, even though the blow be 40 sufficient to cause the carriage to pass slightly beyond the writing point and be returned thereto by the reflex action of the carriage buffer. This defect is completely cured in the 45 present invention because it is not necessary that the carriage pass beyond the writing

point at all, as already stated. If the reader consult the disclosure of the said Patent No. 1,411,997 and compare it with this disclosure, it is thought the difference will be perfectly plain to him. 55

In the drawings:

Fig. 1 is a rear elevation of the well known Elliott Fisher typewriting machine with my device applied thereto.

Fig. 2 is a sectional view of my device 60 taken on the line 2—2 of Fig. 1, showing the parts in their normal positions.

Fig. 3 is a similar view showing the positions of the parts just after the tabulator key 65 has been actuated, the letterfeed disengaged, and before the impact of the tabulator stops with each other.

Fig. 4 is a view partly in section taken upon the line 4—4 of Fig. 1, and showing the parts 70 in their normal positions as in Fig. 2.

Fig. 5 is a similar view showing the positions which the parts assume after the tabulator stops have collided with each other.

Fig. 6 is a perspective view of the toothed locking apron. 75

Fig. 7 is an enlarged fragmentary view showing the arrangement of the buffer springs.

Fig. 8 is a similar view enlarged sufficiently 80 to show the action of the toothed apron with respect to the locking stud, and also the peculiar formation of the stud.

Fig. 9 is a similar view showing the position of the locking bail after the stops have 85 collided with each other.

Fig. 10 is a cross sectional view taken on the line 10—10 of Fig. 1.

Fig. 11 is a fragmentary plan view showing the arrangement of the dash pot mechanism.

Fig. 12 is a fragmentary view of the carriage feeding mechanism.

My device is shown in the drawings as attached to the well known Elliott Fisher typewriting machine, although it will be understood that the device can be attached to, or made a part of, any other form of typewriting machine which involves a framework and a carriage movable thereon. Reference numeral 1 marks the carriage; 2, the framework or bed; 4, the usual rolling frame hav- 95 100

ing wheels 5 which run upon tracks 6 extending longitudinally of the bed; 7, the traction wheels upon the carriage 1 which roll upon tracks 8 upon the rolling frame, whereby 5 the carriage has a transverse movement upon the rolling frame and the rolling frame in turn has a longitudinal movement with respect to the bed. 9 marks the wires which connect the rock shafts 10 with the usual type 10 levers (not shown). Each of the rock shafts has an out-turned end 11 (Figs. 2 to 5) to which is connected a link 12 which in turn is similarly connected to one of the tabulator plungers 13, pivoted at 14 to a housing 15, 15 so that an operation of one of the usual type levers causes its corresponding plunger to move about its pivot whereby its nose 16 is projected into the path of the tabulator stops 17, to arrest the carriage in a tabulating movement, the plungers being returned to their normal positions, against a limit stop 18 by springs 19 and 20. 21 marks the usual cross bar universally acted upon by all the plungers 13. 22 is the usual spring motor drum connected to the carriage by a tape 23. 24 is the usual casting secured to the carriage by screws 25 (Fig. 12) and within which is mounted the feed wheel 25—a having teeth 26 with which coacts the feed pawl 27. The position of the pawl when a tabulator stop 17 is in contact with a projected plunger 13, during a tabulating operation, is shown in dotted lines (Fig. 12). 28 indicates the usual tabulator keys shown in dotted lines (Fig. 1), two 25 only of which are shown,—all according to the usual construction of the well known Elliott Fisher typewriting machine.

Secured by screws 28—a at each side of the rolling frame 4, are L-shaped brackets 29 upon which are mounted blocks 30, which are permitted a slight rotative movement by reason of screws 31 which pass through the blocks and into the brackets (Figs. 10 and 11). This rotative movement of the blocks is provided so that the blocks will keep in perfect alignment with each other for a purpose which will presently appear.

The blocks are channelled to receive bars 32 which slide within the channels. 33 are 30 keeper plates for the bars, firmly secured to the blocks by screws 37. 34 marks an extension having up-turned ends 35 (Figs. 10 and 11), one of which is firmly secured at 36 to the rolling frame and the other is drilled 35 and tapped to receive a screw 37—b which firmly secures to it a dash pot 38 having a mushroom valve 39 interposed between two washers 40 which are in turn firmly secured to the outer end of one of the bars 32, by 40 means of a screw 41. The extreme left hand end (Figs. 1 and 11) of that bar is secured by a screw 42 to a bracket 43 which is milled across its undermost surface so as to leave lugs 44 (Fig. 2) which straddle the usual tabulator stop bar 45, a screw 46 serving to firmly

bind the bracket 43 to the stop bar. The foregoing describes the manner of slidably mounting the stop bar at its right hand end (Fig. 1) upon the rolling frame and the same also describes the manner of mounting the opposite end of the bar, with the exception, of course, of the details of the dash pot, which occurs upon one side of the device only. Upon the stop bar 45 are mounted the usual Elliott Fisher tabulator stops 17, only one of which is shown. Extending from the right hand L-shaped bracket 29, (Fig. 1) is a hook 47 which secures to that bracket one end of a main carriage buffer spring 48, the opposite end of the buffer spring being secured at 49 to one end of a screw threaded shaft 50 having a head 51 at one of its ends, and which slidably passes through an aperture 52 in a guide plate 53, secured by a screw 54 to the rolling frame (Figs. 1 and 7). 55 is a downwardly projecting extension rigid with the lefthand bracket 43 (Figs. 1 and 7) and which is smoothly bored to allow the threaded shaft 50 to slidably pass through the bore. 56 is a supplemental carriage buffer spring which is much weaker than the main buffer spring. The supplemental buffer spring is confined between a threaded nut 57 mounted upon the shaft 50, the nut being free to move with the shaft from its position as seen in Fig. 7 until it contacts with the plate 53. Threadedly mounted upon the shaft 50 is a small washer 58 having apertures 59 to accommodate the end of a wire or other like instrument which may be thrust through the apertures so as to allow the small washer to be turned to advance it either one way or the other along the shaft to any desired position. From this arrangement it will be seen that when the stop bar be thrust to the left and the carriage held stationary, the supplemental carriage buffer spring receives and cushions the thrust but as soon as the downwardly projecting extension 55 contacts with the small washer 58 the main buffer spring will then receive and cushion any further thrust. It will also be seen that the supplemental buffer spring can never be compressed in either direction to such an extent as to completely collapse it and thus cause it to become set or to lose its life and elasticity.

60 indicates brackets (Figs. 1 and 2) one rigidly secured upon each side of the plunger housing 15 by means of screws 61, the upper ends of the brackets being bored through to receive a pintle 62 (Figs. 1 and 2). Upon the pintle is swingably mounted an apron 63 having ratchet teeth 64. A spring 65 is coiled around the pintle (Fig. 3). One of the ends of the spring is secured at 66 to one of the brackets and its opposite end bears upon the apron as at 67 (Figs. 1 and 5), so that the toothed edge of the apron is normally urged in clockwise direction (Fig. 2) about the center represented by the pintle.

Pivoted at 68 to the toothed apron is a trigger 69 (Fig. 4) and bearing upon it is one end of a leaf spring 70 (Figs. 4 and 5) its opposite end being secured at 71 to the inner 5 surface of the apron 63 (Figs. 4, 5 and 6) so that when the parts are in their normal positions as seen in Fig. 4, the trigger holds the apron in the position as seen in that figure, so that the carriage is free to be moved 10 in either direction. It will be understood that the leaf spring 70 is very much weaker than the coiled spring 65 and its function is to always urge the trigger 69 towards its position as seen in Fig. 4. 72 is a bail having 15 its upturned ends 73 pivoted at 74 to the brackets 43 (Fig. 4). The bail drops by gravity to its normal position as seen in full lines in Figs. 2 and 9. Each of the tabulator plungers 13 is notched as at 75 (Figs. 2 and 20 5). 76 is a cam member secured by screws 77 to one of the L-shaped brackets 29 (Fig. 9). Each of the usual Elliott Fisher tabulator stops 17 is provided with an upstanding stud 78 (Figs. 7 and 8) which is normally out of 25 the path of the teeth 64 of the apron 63 but which are adapted to co-act with those teeth when a tabulator stop 17 collides with a projected plunger 13, as will now be described.

Operation

Whenever one of the usual Elliott Fisher tabulator keys 28 be depressed to release the usual Elliott Fisher letterfeeding mechanism (Fig. 12) with a simultaneous projection of 30 a corresponding tabulator plunger 13, and a resultant movement of the carriage in letterfeed direction (Fig. 3) the carriage of course moves under the influence of its usual motor mechanism until one of the tabulator stops 40 17 collides with the projected plunger, all exactly in the well known manner of operation of the Elliott Fisher typewriting machine. However, it is obvious that instantly following 45 the operation of the tabulator key 28, the rebound locking mechanism was set, the parts assuming their positions as seen in Fig. 3. From an inspection of Fig. 4 it will be seen that the trigger 69 is substantially in the 50 shape of a human foot, the lowermost point of the trigger corresponding to the toe of the foot and the point or corner immediately above it corresponding to the heel. A line drawn from the point of contact of the heel with the bracket 60 to the pivot 68 of the trigger, as these parts appear in Fig. 4, is 55 much shorter than a similar line drawn between these points as the parts appear in Fig. 5. That is to say, as the trigger is rotated about its pivot from the position shown in Fig. 4 to the position shown in Fig. 5, the distance between the bracket 60 and the apron 63 necessary to be spanned by the trigger in order to prop up or hold the apron teeth 64 out of the plane of the stud 78 increases and, since the dimensions of the trig-

ger are of course constant, the apron must fall to its Fig. 5 position whenever the trigger is so rotated. The rebound locking mechanism is set by reason of the swinging forward of the plungers 13 to the position shown 70 in Fig. 5 which of course move the bar 21 with it, by reason of the fact that the bar 21 extends across the front faces of all the plungers. The cross bar normally lying behind the trigger 69 will of course cause the trigger to move across its center 68 from its Fig. 4 position to its Fig. 5 position, with a resultant movement of the trigger 69 in clockwise relation to the position seen in Fig. 5 by virtue of the heavy spring 65 about the 80 pivot 62.

When the tabulator key 28 was operated, the feed pawl 27 was caused to move from its full line position to its dotted line position in Figure 12, allowing the carriage to move freely in letterfeed direction, as usual in any tabulating operation. This movement continues until the plunger 13 collides with the tabulator stop 17. Before the instant of this collision, the carriage with its apron has been moving freely in letterfeed direction, but the collision of the plunger 13 with the stop 17 causes the carriage to pick up stop bar 45 and from that time on the carriage, apron, stop bar and stud are all moved on together in letterfeed direction beyond the point of collision and against the action of the buffer spring. Before said collision of the stops, the teeth 64 first collided with the studs 78 but the apron freely chattered or rolled over the stud 78 until the collision of the plunger 13 and the stop 17 occurred. At that time, the teeth 64 assumed the dotted line position shown in Figure 8 and then all the parts just enumerated moved on together. 90 On the reflex action of the buffer spring, all these parts were returned together in contra-letterfeed direction to the point where the collision of the tabular stops took place, that is, the printing point, and when they were so returned, the parts were all in their operative positions.

All the parts enumerated have now made a complete excursion from the printing point to the left in Figure 8 and back to the printing point and no farther, because the stop rod cannot be moved farther to the right for the reason that it is now against its limit stop in that direction, that is, the block 30, and neither can the carriage be moved farther to the right because of the teeth 64, as already explained. The carriage has now been returned to the printing point by the action of the buffer spring 48 of the carriage, but the rebound trap is not yet unlocked or unset but, on the contrary, is still firmly locked and cannot possibly become unlocked until the carriage again starts to move to the left (Figure 8), that is, in letterfeed direction. Thus, of course, the carriage is now free to do for 100 105 110 115 120 125 130

the distance of about one letter space only because the pawl 27 is sure to be caught by the notch on the feed wheel which is just to the left of the pawl in Figure 12. This letter space movement of the carriage is clearly sufficient to cause the tooth 64, which is just to the right of the stud 78 (Figure 8) to ride up freely upon the cam face of the stud 78 until it reaches its full line position (Figure 8).

This upward movement of the apron 63 permits the trigger 69 to return to its normal position, as shown in Figure 4, until a subsequent tabulating operation. The carriage is now free to be moved in either direction because the apron 63 is in the position indicated in full lines in Figure 8 and will not, of course, interfere with carriage movement in either direction. The carriage, by this time, comes again under control of its motor mechanism, which draws the carriage again in letterfeed direction and causes the tooth of the apron, which had been in engagement with the stud 78, to ride up over the stud in letterfeed direction from its position as shown in dotted lines to its position as seen in full lines in Fig. 8, permitting the trigger 69, the projected plunger, the bail and other parts to return to their normal positions as seen in Figs. 2 and 4 and allowing the carriage to move one letter space in letterfeed direction (Fig. 12) and the letterfeeding mechanism to re-engage at that exact point.

It will be noted that the stud 78 (Fig. 8) is of approximately the same contour as the teeth 64 of the apron 63 with the exception that the stud does not represent a true point as do the teeth, but is chamfered off as plainly shown. The result of this is that if, due to wear, inaccurate shop work, or the like, the trigger 69 should in time fail to prop or hold the apron 63 in its position as seen in Fig. 4, thus allowing the teeth of the apron to descend slightly below the plane of the top of the stud, then the chamfered portion of the stud will allow the teeth of the apron to freely pass to the right by a corresponding movement of the carriage, (Fig. 8) the stud offering no interference, because the apron teeth would ride over the small chamfered edge of the stud.

I have shown that the rebound lock effectively traps the carriage and prevents rebound when the carriage cushion be employed, and it is obvious that the carriage will be trapped in exactly the same manner and rebound rendered impossible when the carriage cushion, dash pot, bail and the notches in the plungers, be dispensed with. In such case the tendency of the carriage to rebound follows immediately upon the impact of the tabulator plunger with the tabulator stop,—whereas when a carriage cushion be employed the tendency to rebound occurs an instant after such impact. However, in either case,

rebound is impossible because the rebound trap is set before the impact and the carriage permitted to move one step in letterfeed direction after the tabulator plunger has freed itself from the tabulator stop. In the use of a carriage cushion there is no time lost because the operator continues pressure upon the tabulator key until the tabulator plunger and stop collide with each other, just as is usual in all tabulating operations, and experimental proof has shown that the time required for a rapid operator to move the hand from the depressed tabulator key to the selected type or character key, and to depress that key its full stroke so as to carry the type into contact with the paper,—is considerably greater than the time required for the cushion to function and allow the carriage to come to complete rest at the writing point. I prefer, of course, to use a carriage cushion, but in correspondence typewriting machines of relatively small cost and having relatively light carriages, the cushion may be dispensed with, if desired.

I claim:

1. In a typewriter, tabulating mechanism, a rebound preventing trap, means independent of the movement of the typewriter carriage for setting the trap, and automatic means which insures the maintenance of the trap in a set condition after the carriage is arrested by the tabulating mechanism and until the carriage resumes its letterfeed travel after such arrest.

2. In a typewriter, tabulating mechanism, a rebound preventing trap, means independent of the movement of the typewriter carriage for setting the trap, automatic means which insures the maintenance of the trap in a set condition after the carriage is arrested by the tabulating mechanism and until the carriage resumes its normal letterfeed travel after such arrest, and a buffer for the carriage.

3. In a typewriter, the combination of a rebound preventing trap, means for setting the trap, and means which insures the upsetting of the trap only after the arrest of the carriage by the tabulating mechanism and following the letterfeed travel of the carriage immediately after such arrest.

4. In a typewriter, tabulating mechanism, a carriage rebound trap, means for setting the trap, and means acted upon by the carriage movement in letterfeed direction to unset the trap.

5. In a typewriter, tabulating mechanism, a carriage rebound trap, and means for setting the trap, the said trap comprising means acted upon by the carriage movement in letterfeed direction only to unset the trap.

6. In a typewriter having a frame and a carriage movable thereon, letterfeeding mechanism, a carriage cushion and means including a rebound preventing trap which takes complete control of the carriage move-

ment when the carriage reaches the printing point in a tabulating operation, said means maintaining such control without manual assistance until the carriage is momentarily arrested by the rebound preventing trap at the printing point preparatory to the final arrest of the carriage at that point by said letterfeeding mechanism.

7. In a typewriter having a frame and a carriage movable thereon, letterfeeding mechanism, a carriage cushion, means which includes a rebound preventing trap mounted partly on the carriage and partly on the frame, which takes complete control of the carriage movement when the carriage reaches the printing point in a tabulating operation and continues such control without manual assistance until the carriage is momentarily arrested at the printing point by said rebound preventing trap preparatory to the final arrest of the carriage at that point by the letterfeeding mechanism.

8. In a typewriter tabulating mechanism, a rebound preventing trap, means for springing the trap immediately following an actuation of a tabulator key incident to the operation of the tabulating mechanism, and means which insures the unspringing of the trap at the printing point as a result of the letterfeed movement of the carriage only.

9. In a typewriter including step by step letterfeed mechanism, tabulating mechanism including stops, a rebound preventing trap, means for setting the trap following the actuation of a tabulator key, means which preserves the trap in a set condition independent of any further actuation of the tabulator key, and means acted upon by the letterfeed movement of the carriage to unset the trap.

40 10. In a typewriter including step by step letterfeed mechanism, tabulating mechanism including stops and tabulator keys, a carriage buffer, a rebound preventing trap, means for setting the trap following the actuation of a tabulator key, means for preventing the unseting of the trap until the carriage reaches the printing point in a tabulating operation, and means acted upon by the letterfeed movement of the carriage to unset the trap.

In testimony whereof I affix my signature.
FREDERICK P. GORIN.
